UNITED STATES PATENT OFFICE.

CHARLES A. GLOEKLER, OF PITTSBURG, PENNSYLVANIA.

DESIGN FOR A MEAT-RACK.

SPECIFICATION forming part of Design No. 19,179, dated June 25, 1889.

Application filed May 22, 1889. Serial No. 311,732. Term of patent 14 years.

To all whom it may concern:

Be it known that I, CHARLES A. GLOEKLER, of Pittsburgh, in the county of Allegheny and State of Pennsylvania, have invented a new and useful Design for Meat-Racks, of which the following is a specification.

The new design consists in the shape, the ornamentation, and the combined shape and ornamentation of the meat-rack.

10 The design is illustrated in the accompanying drawing, in which is shown a perspective view of the newly-designed rack.

The rack is composed of curved bars A A, curving upwardly at their centers and having at their outer ends upwardly-turning scrolls a a. These bars A are the ones which carry the meat-hooks b b. The upper rack-bar A supports a vertically and upwardly extending device B, representing a steel, and 15 two inclining devices C D, representing a cleaver and knife, respectively, which incline toward each other and toward the steel B. Supported horizontally by the steel, cleaver, and knife is a device E, representing a saw, 20 and the point of the steel B is surmounted by 25

a representation F of a steer. On either side of these butchers' emblems the upper rack-bar A is ornamented by conventional scrolls c c. The ends of the rack-bars A are supported by the ends of curved brackets G G of 30 the shape shown in Fig. 2, these brackets being carried by vertical rods II, and the several brackets on each rod extending out to different extents. The vertical rods II are provided on the edge opposite the brackets G G with 35 curved brackets I I, as shown, and these brackets are attached to curved supporting-brackets J J, as shown.

I claim as my invention—

The design for the shape and ornamentation of a meat-rack, substantially as shown 40 and described.

In witness whereof I have hereunto signed my name in the presence of two subscribing witnesses.

CHARLES A. GLOEKLER.
